SLIDING-DOOR STOP.

1,145,974.

Specification of Letters Patent.

Patented July 13, 1915.

Application filed March 4, 1915. Serial No. 11,943.

To all whom it may concern:

Be it known that I, FRANK COE, a citizen of the United States, and a resident of Walled Lake, in the county of Oakland and State of Michigan, have invented a new and Improved Sliding-Door Stop, of which the following is a specification.

In the use of sliding doors, as installed on barns and other outbuildings, much annoyance is experienced because the momentum of the door, as it is shoved edgewise in being opened, is often sufficient to cause it to run off the end of the track. Rigid stop members or bumpers are commonly used to prevent this action, but the shock of the door against these members is very apt to cause it to jump laterally from the track. Both of these difficulties are increased in case the end of the track inclines downwardly away from the door opening, as often happens; on the other hand, when the track inclines in the opposite direction there is a tendency for the door to slide partly or wholly shut, which, besides being of annoyance to the user, renders the door liable to be knocked from the track by animals that attempt to pass through the partly closed opening.

The above difficulties are entirely overcome in the present invention, which consists in a resilient buffer so arranged as to receive the edge of the door as it approaches the limit of its movement.

It also consists in such a buffer having means for resiliently retaining the door in open position; and it further consists in the details of construction shown, described and particularly pointed out in the subjoined claims.

In the drawings, Figure 1 is a perspective view from the outside of the building showing the buffer in position, the door being indicated in dash lines. Fig. 2 is a view from the right end of Fig. 1. Fig. 3 is a transverse central section of Fig. 1. Fig. 4 is a fragmentary plan view of a modification. Fig. 5 is a front view of a further modification, parts being broken away. Fig. 6 is a fragmentary section on the line 6—6 of Fig. 5. Fig. 7 is a fragmentary plan view corresponding to Fig. 5, parts being broken away. Fig. 8 is a perspective view of the shock receiving member shown in Fig. 5. Fig. 9 is a longitudinal section through a modified form of resilient retaining member

in engagement with the outer surface of a door.

Similar reference characters refer to like parts throughout the several views.

In the embodiment of my invention shown in Figs. 1 to 3, inclusive, 1 indicates a base plate of metal that may be secured to the outer surface of the building by screws 2 and 3, the latter of which, together with the screw bolt 4, serve to hold rigidly in place on the base plate at the end remote from the door opening the clip 5 having the outwardly projecting flange 6. This flange is perforated to receive a bolt 7 that also passes through the slot 8 in an end portion 9 of a resilient door clamping plate 10, the end of which, nearest the door opening, is slotted at 11 and bent at 12 to inclose the shaft 13 of a roller 14. This roller, it will be understood, is arranged to contact with the outer face of the door and swings the resilient clamping member outwardly about its end 9; the bolt 7 and slot 8 afford means for adjusting the door clamping plate in respect to the base plate to accommodate doors of different thickness.

The door clamping plate is slotted at 15 and the base plate is slotted at 17, the edges 18 of the latter being undercut as shown in Fig. 3. Mounted to slide in these slots is a contact or buffer plate 20 for the edge of the door; this plate has its inner end 21 of flared or dovetailed form to fit the edge of the slot 15, and its outer end is provided with the guiding projection 23 that projects through the slot 15. The plate is normally held at the ends of the slots nearest the roller by the coiled spring 25, one end of which is seated against the flange 6 of the clip 5; and the buffer plate is prevented from tipping by the rod 26 that is rigidly secured thereto and passes through a perforation in the flange 6 and through the slot 8.

As the door slides to its open position, it first contacts with the roller 14, as stated above, whereby it is prevented from swinging outwardly, and its momentum is afterward taken up by the plate 20 and spring 25. The strength of the clamping plate 10 may be made such that the roller will exert a pressure on the door sufficient to retain it in open position; and the movement of the clamping plate toward the base plate is limited by the shoulders 29 on the buffer plate.

In the modification shown in Fig. 4, the clamping plate 10 and clip 5 are replaced by a single member 30, which results in a cheaper construction.

5 The formation of the edges 18 on the plate 1 necessitates a machining operation that is avoided in the construction shown in Figs. 5 to 8, inclusive. In this instance the central portion of the base plate 31 is pressed upwardly at 32 and slotted at 33; and the buffer plate 34 is notched at 35 (Fig. 8), and is provided with the end 36 that slides in the depression in the base plate.

As shown in Fig. 9, the roller on the resilient clamping plate may be replaced by a bend 38 that may terminate in an outwardly turned end 39. The door in this instance is preferably reinforced by a face plate 40 having a depressed bend 41 corresponding to the bend 38, and may be extended across the edge of the door at 42 as shown in Fig. 9. This insures a better retaining grip on the door than would otherwise be secured, but it is clear that a similar reinforcing strip may be arranged to coöperate with the rollers 14.

The details of construction may be changed considerably without departing from the spirit of my invention; and it is also apparent that the device may be located in position to receive the door at the end of the closing movement instead of in the position described. I do not, therefore, wish to be limited otherwise than as indicated by 35 the subjoined claims.

I claim:—

1. A stop for sliding doors comprising a base plate adapted to be attached to a fixed support in parallel relation to the door, a resilient clamping plate secured to the base plate and having a body portion in substantially parallel relation thereto, said clamping plate being spaced from the base plate sufficiently to receive the edge of the door and being arranged to exert pressure on its outer face, a buffer plate located between the base plate and the clamping plate in position to be struck by the edge of the door, said buffer plate being movable longitudinally in respect to the base plate, and resilient means for cushioning the impact of the door on the buffer plate.

2. A stop for sliding doors comprising a base plate adapted to be attached to a fixed support in parallel relation to the door, a resilient clamping plate secured to the base plate and having a body portion in substantially parallel relation thereto, said clamping plate being spaced from the base plate sufficiently to receive the edge of the door and being arranged to exert pressure on its outer face, means for adjusting the clamping plate toward or away from the base plate, a buffer plate located between the base plate and the clamping plate in position to

be struck by the edge of the door, said buffer plate being movable longitudinally in respect to the base plate, and resilient means for cushioning the impact of the door on the buffer plate.

3. A stop for sliding doors comprising a support, a resilient clamping plate secured thereto in parallel relation to the door, said clamping plate being spaced from the door sufficiently to receive the edge of the door and being arranged to exert pressure on its outer face, a buffer plate located in position to be struck by the edge of the door, said buffer plate being movable longitudinally in respect to the base plate, and resilient means for cushioning the impact of the door on the buffer plate.

4. A stop for sliding doors comprising a base plate adapted to be attached to a fixed support in parallel relation to the door, a resilient clamping plate secured to the base plate and having a body portion in substantially parallel relation thereto, said clamping plate being spaced from the base plate sufficiently to receive the edge of the door and being arranged to exert pressure on its outer face, a buffer plate located between the base plate and the clamping plate in position to be struck by the edge of the door, said buffer plate being movable longitudinally in respect to the base plate, means for guiding the buffer plate in its movement, a rod for preventing the buffer plate from tipping, and a coiled spring for cushioning the impact of the door on the buffer plate.

5. A stop for sliding doors comprising a base plate adapted to be attached to a fixed support in parallel relation to the door, a resilient clamping plate secured to the base plate and having a body portion in substantially parallel relation thereto, said clamping plate being spaced from the base plate sufficiently to receive the edge of the door and being arranged to exert pressure on its outer face, said base plate having a longitudinal slot, a buffer plate located between the base plate and the clamping plate in position to be struck by the edge of the door, a portion of the buffer plate extending into the slot to prevent the base plate from being withdrawn therefrom, said buffer plate being movable longitudinally in the slot, and resilient means for cushioning the impact of the door on the buffer plate.

6. A stop for sliding doors comprising a base plate adapted to be attached to a fixed support in parallel relation to the door, a resilient clamping plate secured to the base plate and having a body portion in substantially parallel relation thereto, said clamping plate being spaced from the base plate sufficiently to receive the edge of the door and being arranged to exert pressure on its outer face, said base plate and said clamping plate having aligned longitudinal slots, a

buffer plate located between the base plate and the clamping plate in position to be struck by the edge of the door, said buffer plate having portions that extend, respectively, into the slot in the base plate and the slot in the clamping plate, said buffer plate being movable in said slots and being guided by said projecting portions, and resilient means for cushioning the impact of the door on the buffer plate.

7. A stop for sliding doors comprising a base plate adapted to be attached to a fixed support in parallel relation to the door, a resilient clamping plate secured to the base plate and having a body portion in substantially parallel relation thereto, said clamping plate being spaced from the base plate sufficiently to receive the edge of the door and being arranged to exert pressure on its outer face, said base plate having a struck up slotted central portion, a buffer plate located between the base plate and the clamping plate in position to be struck by the edge of the door, a portion of the buffer plate extending into the slot to prevent the base plate from being withdrawn therefrom, said buffer plate being movable longitudinally in the slot, and resilient means for cushioning the impact of the door on the buffer plate.

8. A stop for sliding doors comprising a base plate adapted to be attached to a fixed support in parallel relation to the door, a resilient clamping plate secured to the base plate and having a body portion in substantially parallel relation thereto, said clamping plate being spaced from the base plate sufficiently to receive the edge of the door and being arranged to exert pressure on its outer face, a buffer plate located between the base plate and the clamping plate in position to be struck by the edge of the door, said buffer plate being movable longitudinally in respect to the base plate, resilient means for cushioning the impact of the door on the buffer plate, and a reinforcing plate carried by the door and arranged to co-act with the clamping plate for holding the door in a predetermined position.

9. A stop for sliding doors comprising a base plate adapted to be attached to a fixed support in parallel relation to the door, a resilient clamping plate secured to the base plate and having a body portion in substantially parallel relation thereto, said clamping plate being spaced from the base plate sufficiently to receive the edge of the door and being arranged to exert pressure on its outer face, a buffer plate located between the base plate and the clamping plate in position to be struck by the edge of the door, said buffer plate being movable longitudinally in respect to the base plate, resilient means for cushioning the impact of the door on the buffer plate, and a reinforcing plate

carried by the door and having a depression therein arranged to co-act with the clamping plate for holding the door in a predetermined position.

10. A stop for sliding doors comprising a base plate adapted to be attached to a fixed support in parallel relation to the door, a resilient clamping plate secured to the base plate and having a body portion in substantially parallel relation thereto, said clamping plate being spaced from the base plate sufficiently to receive the edge of the door, a roller carried by the clamping plate in position to contact with the outer face of the door, a buffer plate located between the base plate and the clamping plate in position to be struck by the edge of the door, said buffer plate being movable longitudinally in respect to the base plate, and resilient means for cushioning the impact of the door on the buffer plate.

11. A stop for sliding doors comprising in combination, a support, a resilient plate carried by the support in parallel relation to the door, said clamping plate being spaced from the support a distance sufficient to receive the edge of the door, whereby the movement of the door in a direction at right angles to its own plane is limited when in engagement with the resilient plate, and a buffer plate operably connected to the resilient plate and arranged to cushion the door as it approaches the end of its movement in one direction.

12. A stop for sliding doors comprising two resilient members extending substantially in the same direction, one of the members receiving the impact of the door as it approaches the end of its movement in one direction, the portion of the member upon which the impact of the door is received being arranged to be carried along thereby in accordance with the continued movement of the door, the other resilient member being arranged to bear upon the outer face of the door, whereby any tendency of the latter to move in the opposite direction is overcome.

13. A stop for sliding doors comprising two resilient members one of which is arranged to cushion the door as it approaches the end of its movement in one direction and tending, when the door is at the limit of its movement, to force it back in the direction from which it came, the other resilient member being arranged to press on the outer face of the door to prevent the latter from moving in a direction at right angles to its sliding movement, and the door having a depression in which a portion of the last mentioned resilient member is received, whereby the door is retained after being cushioned.

14. A stop for sliding doors comprising a support and two resilient members, one of

which is arranged to receive the impact of the edge of the door to cushion its sliding movement, the portion of the member upon which the impact is received being carried along by the door the full distance of the continued movement of the latter, the other member being substantially parallel to the line of movement of the door and having one of its ends arranged to insure an easy reception of the door and to press against the outer face of the latter to prevent movement at right angles to the sliding movement.

15. A stop for sliding doors comprising two resilient members, one of which is ar-

ranged to receive the impact of the edge of the door to cushion its sliding movement, the other member being supported from a point in line with and beyond the limit of sliding movement of the door and overhanging the latter to bear upon its outer face.

In testimony whereof I sign this specification in the presence of two subscribing witnesses.
